(57) **CLAIM**

The ornamental design for a light fixture, as shown and described.

DESCRIPTION

FIG. 1 is top perspective view of a light fixture showing my new design;

FIG. 2 is a bottom perspective view thereof;

FIG. 3 is a front elevation view thereof, the rear elevation view thereof, the right side elevation view thereof, and the left side elevation view thereof being substantially the same thereof; and,

FIG. 4 is a bottom plan view thereof.

The broken line showing of the light fixture is included for the purpose of illustrating environmental structure and forms no part of the claimed design.
